D. J. CARTWRIGHT,
DETONATOR FOR HIGH EXPLOSIVE SHELLS.
APPLICATION FILED MAY 4, 1918.

1,331,623.

Patented Feb. 24, 1920.

Inventor:

David J. Cartwright,
By Dodge and Dowd,
Attorney.

UNITED STATES PATENT OFFICE.

DAVID J. CARTWRIGHT, OF NEW YORK, N. Y.

DETONATOR FOR HIGH-EXPLOSIVE SHELLS.

1,331,623.

Specification of Letters Patent. Patented Feb. 24, 1920.

Application filed May 4, 1918. Serial No. 232,623.

To all whom it may concern:

Be it known that I, DAVID J. CARTWRIGHT, a citizen of the United States, residing at New York city, in the county of New York and State of New York, have invented certain new and useful Improvements in Detonators for High-Explosive Shells, of which the following is a specification.

This invention pertains to detonators for high explosive shells and has for its main object the production of a detonator which will be safe under all service conditions and which will likewise function with certainty. A further object of the invention is to provide a detonator which may be reliably employed to detonate a high power explosive, such for instance, as tri-nitrotoluol, and this without the employment of a booster charge. A still further object is to produce a detonator wherein two substances or compounds are employed, one being what may be termed a friction charge or compound susceptible of being exploded or caused to combust upon the entrance of a firing pin or hammer thereinto, while the second, which is exploded by the first charge, causes the explosion of the main bursting charge within the shell.

With these and further objects and advantages in view, as will presently appear, reference is had to the annexed drawing, wherein the detonator is shown in longitudinal section.

In said figure 1 denotes the base of the housing having a centrally disposed opening 2 extending therethrough into a chamber or recess 3, the latter in turn opening into the lower portion of an upper relatively large chamber 4. The wall 5 of the latter is thin or light and the housing or shell will be preferably turned from a single piece of metal, such as brass. Placed within the bottom of chamber 3 and overlying and closing the inner end of opening 2 is a thin disk 6 preferably formed of copper.

A suitable compound (fulminate of mercury) susceptible of being detonated by friction, as for instance, the stabbing action of a firing pin or hammer, is placed within the chamber 3, said compound being, preferably, subjected to a high degree of compression when positioned. Resting upon the lower wall of chamber or cavity 4 and overlying the primary exploding charge just mentioned, is a disk or washer 7, preferably a disk of muslin. The secondary or detonat-

ing charge is compressed within said chamber 4, and will, in practice, be preferably fulminate of mercury. This charge will be likewise subjected to pressure, say 5000 lbs. 60 per square inch, whereas the primary charge may be subjected to 15,000 lbs. pressure to the square inch.

Resting upon the upper portion of the fulminate charge is a disk 8, preferably 65 formed of paper or felt, and overlying such disk is a sealing cap-shaped member 9 formed of copper or other ductile or flexible metal.

As shown in the drawing, when the parts 70 are positioned, the upper end of the wall 5 will be turned inwardly into intimate contact with the upstanding wall of the cap-shaped sealing disk 9, which, during such operation, may also be bent or turned in 75 slightly as clearly shown in the drawing. A water-proof sealing compound 10 will then be placed in the upper end of the housing and overlie and fill the sealing member 9 so as to absolutely preclude the entrance of 80 moisture into the charge.

Fitting over the upper end of the housing is a metallic cap or hood 11 (of copper or other suitable material), the wall of which is thin and made of about the same thickness as the wall 5 of the housing. Said cap makes a close or mechanical fit with the exterior of said wall 5 so that when it is forced to place it will retain its position under all service handling or conditions. A small 90 opening 12 will be formed in the cap or hood in the upper end thereof.

It is conceivable that the primary and exploding charges may be of the same material and loaded at different densities. As 95 will be seen upon reference to the drawing, when the water-proof compound 10 is placed in the upper end of the structure prior to the placement of the hood or cap 11 it tends to settle down and shrink somewhat and to afford an air space between the upper portions thereof and the adjacent overlying wall of the cap or hood 11. The muslin disk or washer 7 interposed between the two charges acts as a septum to prevent chemical reaction between the constituents of the two charges in case they be made or formed of different materials which might react one upon the other and cause a disintegration of the charges and a premature explosion 110 thereof owing to such chemical reaction.

In operation the detonator is placed with-

in the opening provided in the shell and the major portion thereof extends into the chamber within the shell which is loaded with a high explosive, such for instance, as T. N. 5 T. Upon the firing of the shell from the gun, the cap or hood 11 in a measure takes up the shock of the bursting charge of the shell due to the set back of such material when the gun is fired. If the pressure came 10 directly upon the fulminate charge such charge might be prematurely exploded. So, too, the sealing element and the underlying yieldable washer 8 tends to absorb such shock and to render the detonator safe so 15 that no premature explosion will occur. The air space above mentioned also assists in a great measure in relieving the exploding or fulminate charge of the shock of the set back. The paper or felt disk acts as a cushion 20 for the fulminate or other charge within the chamber 4 if through accident the loaded shell should be dropped and strike on its forward end. In other words, while it is sought in the assembling of the various elements to absolutely prevent any movement 25 of the fulminate charge within the chamber, it will be readily appreciated that if a shell were dropped and movement of the charge relatively to the chamber take place 30 a detonation might ensue, but by having the felt or other equivalent disk 8, the chances of such movement are minimized, and, furthermore, the disk would act as a cushion and prevent such a jar or impact as would 35 preclude the explosion of the fulminate. When the shell strikes an object the firing pin is thrown forward and passes through the opening 2 perforating the thin disk 6 and causing an explosion or ignition of the 40 primary charge in the chamber 3. Such charge in turn will cause the fulminate or other charge within the chamber 4 to explode and such explosion will disrupt the housing and its allied parts and effect a detonation of the surrounding high explosive 45 within the shell.

In practice the detonator has been found absolutely safe in handling and in service operation, and likewise has proved highly 50 efficient in effecting the detonation of the bursting charge within the shell.

What I claim as new and desire to secure by Letters Patent is,—

1. In a detonator, the combination of a 55 housing having two chambers therein; a highly compressed compound located in one of said chambers susceptible of being caused to function through the stabbing or penetrative action of a firing pin; a detonating 60 charge located in the other chamber, said detonating charge being caused to act by the functioning of the other charge and a septum located between said charges and normally separating the same to prevent 65 chemical reaction between the same.

2. In a detonator, the combination of a housing having an opening in one end, a friction compound located within the housing adjacent said end; a detonating charge overlying the friction compound; means for sealing such materials within the housing; and a separator formed of muslin between the friction compound and the detonating charge.

3. In a detonator for high power explosive shells, the combination of a housing having an opening in one end; a friction compound overlying said opening; a detonating charge overlying the friction compound; and a cap overlying the upper portion of the housing and serving to absorb the set back of the material which surrounds the detonator upon the firing of the projectile.

4. In a detonator, the combination of a housing having an opening in one end there of for the entrance of a firing pin; a disk of thin metal overlying the inner end of said opening; a friction compound compressed within the housing and resting upon the disk; a second disk overlying said friction compound; a closure for the upper end of the housing, said housing and closure having an interlocking engagement; and a water-proof compound located within the upper end of the housing outside of the closure and serving to seal the parts.

5. In a detonator, the combination of a housing having an opening in one end there of for the entrance of a firing pin; a friction compound located adjacent said opening; an explosive charge located within the housing above the friction compound; a yielding disk overlying the upper end of the explosive charge; and a water-tight closure for the upper end of the housing.

6. In a detonator, the combination of a housing having an opening in one end there of for the entrance of a firing pin; a friction compound located adjacent said opening; an explosive charge located within the housing above the friction compound; a yielding disk overlying the upper end of the explosive charge; a cup shaped closure resting upon the disk within the housing, said closure and the upper end of the housing being inturned to form an interlocking engagement; and a water-proof compound located between the upper end of the housing and the cup shaped closure.

7. In a detonator, the combination of a housing having an opening in one end there of for the entrance of a firing pin; a friction compound located adjacent said opening; an explosive charge located within the housing above the friction compound; a yielding disk overlying the upper end of the explosive charge; a cup-shaped closure resting upon the disk within the housing, said closure and the upper end of the housing being inturned to form an interlocking en-

gagement; a water-proof compound located within the upper end of the housing and the cup shaped closure; and a cap extending over the upper end of the housing and downwardly along the sides thereof.

8. In a detonator, the combination of a housing having an opening in one end thereof through which a firing pin may pass; a thin copper disk overlying the inner end of 10 said opening; a friction compound compressed within the housing over said disk; a muslin disk overlying said compound; an explosive charge compressed within the housing above said muslin disk; a yielding 15 disk overlying the upper end of the explosive charge; a cup shaped closure mounted within the upper end of the housing and resting on the disk just mentioned, said cup shaped closure and the upper end of the 20 housing being inturned to hold the closure in place; a water-proof compound placed

within the cup shaped closure and the upper portion of the housing and serving to seal the same; and a cap mounted upon the upper end of the housing, said cap extending 25 downwardly along the exterior wall of the housing and likewise provided with an opening in the upper face thereof, said opening communicating with the air space left between the under face of the cap and the 30 upper face of the water-proof compound.

9. In a detonator, the combination of a housing or body containing an explosive charge; and a cap overlying the upper end of the housing, an air space being left between 35 the inner face of the cap and the charge whereby premature explosion of the charge by set back in firing will be prevented.

In testimony whereof I have signed my name to this specification.

DAVID J. CARTWRIGHT.
